U.S. Cl. D30—1

FIG. 1

FIG. 2

FIG. 1 is a top and side perspective view of a pet house, showing our new design, the opposite top and side perspective view being substantially a mirror image thereof excluding the openings in the side; and

FIG. 2 is a fragmentary bottom and opposite perspective view thereof.

Portions of the inner and outer surfaces of the figures are stippled to indicate contrast in appearance.

We claim:

The ornamental design for a pet house, substantially as shown and described.
